BURNER

Filed Nov. 11, 1925

INVENTOR:

Arthur A. Yost
BY Harry T. Williams,
ATTORNEY

UNITED STATES PATENT OFFICE.

ARTHUR A. YOST, OF BOSTON, MASSACHUSETTS.

BURNER.

Application filed November 11, 1925. Serial No. 68,347.

The invention to be hereinafter described relates to burners employing oil as a fuel.

In burners of this type the fuel oil is conducted to a delivery nozzle and atomizing fluid, which may be air under pressure or steam, is conducted to the delivery nozzle and there meets, breaks up and promotes combustion of the fuel oil. Heretofore, considerable difficulty has been experienced in properly mixing the atomizing fluid and the fuel oil so as to obtain the best results. One of the purposes of the present invention, therefore, is to provide means for efficiently mixing the atomizing fluid and the fuel oil, and for producing a low pressure flame.

The character of the invention may be best understood by reference to the following description of one good form thereof shown in the accompanying drawing, where-

in:

Fig. 1 is a vertical longitudinal section through a burner embodying the invention;

Fig. 2 on an enlarged scale is a perspective view of the rotary cup having the sets of vanes thereon; and

Fig. 3 is a vertical longitudinal section through a portion of the barrel, the nozzle and the rotary cup.

Referring to the drawing, the burner shown therein as one good form of the invention is provided with a support 1, in the present instance in the form of a short sleeve 3 on a pipe section 5 on a pipe 7 adapted to conduct the atomizing fluid to the burner. To regulate the feed of the atomizing fluid, the pipe section 5 is provided with a disk valve 9 on a shaft 11 having a handle 13, said shaft being held in its different positions of adjustment by a coil spring 15 encircling the shaft and confined between the handle 13 and a side of the pipe section 5.

The support sleeve 3 receives a fuel oil burner or gun comprising a breech 17, a barrel 19 threaded to the breech, and a nozzle 21 threaded to the barrel. Projecting from the breech is a suitable handle 23 adapted to be grasped to thrust the gun into the sleeve 3 to firing position and to retract it from said position. At the bottom of the breech is an opening 25 through which the atomizing fluid may pass from the pipe section 5 into the breech. The breech has a port 27 adapted for communication with the pipe for conducting the fuel

oil to the burner. A pipe 29 has one end threaded into a bore in the rear end of the breech communicating with the port 27, and said pipe extends centrally through the barrel to the nozzle. Adjacent the forward end of the pipe 29 is a spider 31 contributing to the support of the pipe 29 in the barrel. The pipe is smaller than the barrel, and leaves an annular passage 33 through which the atomizing fluid may pass to the nozzle.

A rotary cup 35 is mounted in the nozzle on the forward end portion of the pipe 29, and to facilitate rotation of the cup it is provided with ball bearings 37 having raceways 39 and 41 mounted in the cup and on the forward end portion of the pipe respectively, said raceways being confined between a cap 43 threaded on the inner end of the cup and a washer 45 engaging an internal flange 47 on the cup.

To lubricate the ball bearings there is provided a lubricant receiving cup 49 having a neck 51 extending through a slot 53 in the sleeve 3 and into the breech where it is connected to a union 55 mounted on the pipe 29. A small tube 57 has one end connected to the union and its opposite end connected to the spider 31 referred to. A port 59 (Fig. 3) is adapted to conduct the lubricant from the tube to the ball bearings.

Threaded to the forward end of the fuel oil conducting pipe 29 is a head 63 (Fig. 3) having a downwardly directed port 65 for delivering the fuel oil to the inner surface 67 of the cup. The inner surface of the forward portion of the cup is tapered and flares outwardly.

Mounted on and projecting outward from the cup into the space between the cup and the inner surface of the nozzle are a forward set of vanes 69 and a rearward set of vanes 71. Preferably these vanes almost reach and barely clear the inner surface of the nozzle. The vanes of both sets have substantial length, but the vanes of the rear set, in the present instance are shorter than the vanes of the front set. The vanes of the front set are inclined in respect to the axis of the rotary cup and have a slight longitudinal twist. They are disposed to cause the cup to rotate in a clockwise direction on passage of the atomizing fluid through the spaces between the vanes. The vanes of the rear set are disposed in a different direction from the vanes of the front set, and in the

present instance of the invention, are inclined in respect to the axis of the rotary cup and in a direction opposite to that of the front set of vanes. The vanes of the rear set are so disposed that on passage of the atomizing fluid between them, they have a tendency to rotate the cup in a contra-clockwise direction, but since the vanes of the rear set are shorter than the vanes of the front set, they operate to reduce the speed of rotation of the cup. The resultant speed will depend upon the difference in the lengths of the vanes of the two sets or in the difference in the angles or sizes of the vanes of the two sets. The number, width and angle of the vanes may be varied, provided the construction is such that they have the speed reduction effect required. The speed of rotation of the cup should be so controlled that the streams of atomizing fluid issuing from the spaces between the front vanes will whirl in a contra-clockwise direction.

Preferably the cup comprises a front section 73 and a rear section 75 threaded together so that they may be detachably connected and admit vane sets of varying character to be assembled in cooperating relation. If it is desired to obtain a greater speed of rotation of the cup than had by the vanes shown, a cup section having vanes shorter than the vanes 71 may be substituted for the cup section 75. On the other hand, if it is desired to give the cup a slower speed of rotation than had by the vanes shown, a cup section having longer vanes than the vanes 71 may be substituted for the cup section 75.

In operation, the fuel oil will be conducted through the pipe 29 to the head 63, and thence to the inner surface of the rotary cup. The flare of the inner surface of the latter will cause the fuel oil to move outward to the delivery end of the cup, and the fuel oil will issue therefrom whirling in a clockwise direction caused by the drag of the inner surface of the cup on the fuel oil and the urging of the fuel oil toward said surface by the influence of centrifugal force.

The atomizing fluid will pass through the annular passage 33 in the gun through the spaces between the arms of the spider, and thence through the spaces between the vanes 71 of the rear set. The atomizing fluid streams issuing from the spaces between the vanes 71 will be directed to the spaces between the vanes 69 of the front set with a whirl in a clockwise direction, and the streams of the atomizing fluid issuing from the spaces between the vanes of the front set at the delivery end of the nozzle will be caused by said vanes to have a whirl in a contra-clockwise direction which is opposite to the whirl of the fuel oil delivered from the cup. As a consequence, the fuel oil will be thoroughly broken up or atomized, and

the atomizing fluid will be thoroughly mixed with the fuel oil and insure efficient combustion. The vanes 69 of the front set have substantial length sufficient to insure the direction and whirling of the atomizing fluid with contra-clockwise motion. The vanes of the rear set will retard the speed of rotation of the cup, and will reduce the speed or force of the flame so that the latter instead of being projected in a stream of short radius from the delivery end of the gun, will flare outwardly through a large radius adjacent the delivery end of the gun.

The low pressure, slow moving and whirling flame thus produced, results in efficient combustion, and the character of the flame is such that it reaches a desirably large area of heating surface.

It will be understood that the invention is not limited to the specific embodiment shown, and that various deviations may be made therefrom without departing from the spirit and scope of the appended claims.

What is claimed is:

1. A burner for atomized liquid fuel comprising, in combination, a nozzle, a rotary cup in the nozzle and spaced from the inner surface of the nozzle, means to deliver liquid fuel into the rotary cup, means to deliver atomizing fluid to the space between the cup and the nozzle, a set of vanes on and projecting out from the cup and inclined in respect to the axis of the cup for causing rotation of the cup on passage of the atomizing fluid between said vanes, and a set of vanes on and projecting out from the cup for receiving the atomizing fluid and arranged to retard the speed of rotation of the cup.

2. A burner for atomized liquid fuel comprising, in combination, a nozzle, a rotary cup in the nozzle and spaced from the inner surface of the nozzle, means to deliver liquid fuel into the rotary cup, means to deliver atomizing fluid to the space between the cup and the nozzle, two sets of vanes on and projecting out from the cup and adapted to have the atomizing fluid pass between the vanes of the sets, the vanes of one of the sets being disposed to be acted upon by the atomizing fluid and cause rotation of the cup, and the vanes of the other set being disposed to be acted upon by the atomizing fluid and reduce the speed of rotation of the cup obtainable by the first set of vanes.

3. A burner for atomized liquid fuel comprising, in combination, a nozzle, a rotary cup in the nozzle and spaced from the inner surface of the nozzle, means to deliver liquid fuel into the rotary cup, means to deliver atomizing fluid to the space between the cup and the nozzle, two sets of vanes on and projecting out from the cup and adapted to be acted upon progressively by the atomizing fluid passing through the space

between the cup and the nozzle, the vanes of one of said sets being longer than the vanes of the other set, that the cup may be rotated by action of the atomizing fluid on the 5 longer vanes as reduced by the action of the atomizing fluid on the shorter vanes.

4. A burner for atomized liquid fuel comprising, in combination, a nozzle, a rotary cup in the nozzle and spaced from the inner 10 surface of the nozzle, means to deliver liquid fuel into the rotary cup, means to deliver atomizing fluid to the space between the cup and the nozzle, and sets of vanes on and projecting out from the cup adapted to be acted 15 upon by the atomizing fluid passing through the space between the cup and the nozzle, the vanes of one of said sets being inclined to the axis of the cup for causing rotation of the cup, and the vanes of the other set being inclined in a direction opposite to the 20 inclination of the vanes of the first set to retard the speed of rotation of the cup.

5. A burner for atomized liquid fuel comprising, in combination, a nozzle, a rotary cup in the nozzle and spaced from the inner surface of the nozzle, means to deliver liquid fuel into the rotary cup, means to deliver atomizing fluid to the space between the cup and the nozzle, two sets of vanes on 25 and projecting out from the cup and adapted to be acted upon by the atomizing fluid passing through the space between the cup and the nozzle, the vanes of one of said sets being disposed at an angle for causing rotation of the cup, and the vanes of the other set being disposed at an angle to retard the 30 speed of rotation of the cup, the cup rotating vanes being disposed nearer the delivery end of the nozzle than the retarding vanes.

6. A burner for atomized liquid fuel com-

prising, in combination, a nozzle, a rotary cup in the nozzle and spaced from the inner surface of the nozzle, means to deliver liquid fuel into the rotary cup, means to deliver atomizing fluid to the space between the cup and the nozzle, two sets of vanes mounted on and projecting out from the cup and adapted to be acted upon by the atomizing fluid passing through the space between the cup and nozzle, one of said sets of vanes being disposed to cause rotation of the cup and the other set of vanes being disposed to retard the speed of rotation of the cup, the 45 retarding set of vanes being detachably secured to the cup. 50

7. A burner for atomizing liquid fuel comprising in combination, a barrel having a nozzle, a fuel conducting pipe in the barrel and spaced from the inner surface of the latter to leave an annular passage for conducting 55 atomizing fluid, a rotary cup for receiving the liquid fuel from the pipe, and means for rotating the cup including two sets of vanes on the cup disposed in different directions that one of said sets of vanes may reduce the speed of rotation of the cup caused by passage of the atomizing fluid between the vanes of the other set.

8. A burner for atomized liquid fuel comprising, in combination, a nozzle, a rotary cup in the nozzle having an outwardly flared delivery mouth, said cup being smaller than the nozzle to leave a passage between them, and two sets of vanes on the cup and in 60 said passage to be acted upon progressively by the fluid, one of said sets of vanes being disposed to promote rotation of the cup and the other set of vanes being disposed to retard the speed of rotation of the cup. 65
